UNITED STATES PATENT OFFICE.

ERNEST ALSCHULER, OF NEW YORK, N. Y.

BATTERY HAND LAMP.

1,404,259.

Specification of Letters Patent. Patented Jan. 24, 1922.

Application filed June 21, 1920. Serial No. 390,511.

To all whom it may concern:

Be it known that I, ERNEST ALSCHULER, a citizen of the United States, and residing at New York, New York, have invented the 5 new and useful Improvement in Battery Hand Lamps, of which the following is a specification.

This invention relates to battery hand lamps of the type adapted to be lighted 10 while held in the hand by the manipulation of a switch on the casing, and more particularly to such lamps as are provided with an all metal casing.

As such lamps are often carried in tool 15 boxes and similar places and accidental contact is liable to operate the switch, thereby lighting the lamp and exhausting the battery unnecessarily, it is desirable to provide means for rendering such accidental exhaustion of the battery impossible.

One of the objects of this invention, therefore, is to provide means for obviating the danger of accidental closing the battery circuit by manipulation of the switch.

20 Another object of this invention is to provide novel means for insulating the internal circuit conductors.

Another object of this invention is to provide a lamp structure which is simple and 25 cheap to manufacture and reliable in operation.

Further objects will appear from the detail description taken in connection with the accompanying drawings in which:

30 Figure 1 is a sectional view of a battery hand lamp embodying this invention;

Figure 2 is an enlarged detail view showing the structure for supporting the reflector;

40 Figure 3 is an enlarged detail view showing the construction of the auxiliary circuit opening device; and,

Figure 4 is a view showing the end cap 45 partly unscrewed so as to open the battery circuit.

Referring now to the accompanying drawing, 1 designates the metallic casing, 2 the battery, one of whose terminals contacts with one of the terminals of the lamp 50 3, mounted in the reflector 4 in the usual way. The upper end of the casing 1 is threaded to receive a threaded sleeve on the housing 5, which encloses the reflector. The upper end of the reflector bears against the

lower face of a lens 6, which is held in 55 place by the ring 7, screwing on to the upper end of the housing 5. These parts may be of the usual construction well known in the art.

The housing 5 is bent inwardly to form 60 an internal annular shoulder as shown at 8. A metallic ring 9 is mounted on the shoulder 8. The ring 9 is formed to receive and retain an insulating ring 10 which is arranged to engage the reflector 4 at an intermediate 65 portion thereof, so as to support and center said reflector in the casing. The outer end of the reflector may be of smaller diameter than the ring 7, so as to be spaced therefrom for insulation purposes. The reflector 4 is 70 securely held in position by being confined between the ring 9 and the lens 6.

The switch 20, which may be of the construction described and illustrated in No. 1287262, of December 10, 1918, is mounted 75 on the casing and in electrical connection therewith. This switch has a contact 11 insulated from the casing. A conductor 12 passes upwardly within the casing being attached near its upper end by means of a 80 rivet 13 to an insulating collar 14 mounted in the upper end of the casing, and adapted to support and insulate the conductor 12. Said conductor extends beyond the casing a sufficient distance to contact with the reflector, passing inside of the ring 10. The conductor 12 is insulated from the casing by means of an insulating strip 15 which is attached to the casing by means of the rivet 16, and the conductor 12 is attached to the strip 85 15 by means of the rivet 11.

A perforation 17 in the casing is adapted to insulate the rivet 11 therefrom and a similar perforation 18 in the conductor 12 is adapted to insulate the upper rivet 16 90 95 from said conductor.

A metal end cap 19 of the usual construction is provided to close the lower end of the casing. Within the end cap, but insulated therefrom, by means of the flanged 100 insulating washer 21, is a metal disc 22 having an overturned flange 23 adapted to receive and retain a coil of the battery supporting spring 24, in the battery circuit. The flange 23 is arranged to contact with 105 the flange 25 in the end of the casing to complete the battery circuit.

It will be seen that when the cap 19 is un-

screwed so as to break contact between the flanges 23 and 25, it will be impossible to close the battery circuit by manipulation of the switch 20.

5 It will further be seen that by means of the ring 10 and the insulation 14 and 15, that the upper branch of the lamp circuit is entirely insulated from the casing, so that by breaking contact between the flanges 23 and 25 the casing is entirely insulated from the battery circuit. It will also be seen that when the housing 5 is screwed home upon the casing that the conductor 12, which passes up inside of the insulating ring 10, will be brought into forcible contact with the reflector 4 and will be sustained in such contact by the ring 10.

10 It will be seen, therefore, that this invention accomplishes its objects by providing a construction whereby accidental closing of the battery circuit may be rendered impossible. It will also be noted that novel means are provided for insulating the internal circuit conductors from the casing. 15 It will further be seen that the reflector support is of such construction as to effectively support and fix the reflector.

20 It is obvious that various changes may be made in the details of construction without departing from the spirit of this invention; it is, therefore, to be understood that this invention is not to be limited to the specific details shown and described.

25 Having thus described this invention, what is claimed is:

30 1. In a battery hand lamp having a metal battery-receiving casing, a lamp in the casing, a metal reflector therefor, and a switch on the casing adapted to normally connect the lamp with the battery, a lamp circuit having two branches, one branch including part of the casing, and one branch, including the reflector, and being entirely insulated from the casing, and means for disconnecting the casing from the battery.

35 2. In a battery hand lamp having a metal battery-receiving casing, a lamp in the casing, a metal reflector therefor and a switch on the casing adapted to normally connect the lamp with the battery, a lamp circuit having two branches, one branch including part of the casing, and one branch, including the reflector, and being entirely insulated from the casing, a movable cap on the casing, and means adapted upon movement of said cap to disconnect the casing from said circuit.

40 3. In a battery hand lamp having a metal, battery-receiving casing, a lamp in the casing, a metal reflector therefor and a switch on the casing adapted to normally connect the lamp with the battery, a lamp circuit having two branches, one branch including part of the casing, and one branch including

45 the reflector, and being entirely insulated from the casing, a movable cap on the casing, and means in said cap but insulated therefrom adapted to normally maintain said circuit, and adapted upon movement of said cap to break said circuit.

50 4. In a battery hand lamp having a metal battery-receiving casing, a lamp in the casing, a metal reflector therefor, and a switch on the casing adapted to normally connect the lamp with the battery, a lamp circuit having two branches, one branch including part of the casing, and one branch including the reflector and a conductor connecting the reflector with the switch, means for insulating the reflector from the casing, means for insulating said conductor from the casing, and means for disconnecting the casing from the battery.

55 5. In a battery hand lamp having a metal battery-receiving casing, a lamp in the casing, a metal reflector therefor, and a switch on the casing adapted to normally connect the lamp with the battery, a lamp circuit having two branches, one branch including part of the casing, and one branch including the reflector and a conductor connecting the reflector with the switch, insulating means adapted to support the reflector and center the same in the casing, means for insulating said conductor from the casing, and means for disconnecting the casing from the battery.

60 6. In a battery hand lamp having a metal battery-receiving casing, a lamp in the casing, a metal reflector therefor, and a switch on the casing adapted to normally connect the lamp with the battery, a lamp circuit having two branches, one branch including part of the casing, and one branch including the reflector and a conductor connecting the reflector with the switch, insulating means adapted to support the reflector and sustain said conductor, means for insulating said conductor from the casing, and means for disconnecting the casing from the battery.

65 7. A battery hand lamp, comprising, a metal battery-receiving casing in the lamp circuit, an end cap mounted on said casing, and an element mounted in but insulated from said cap, connected with the battery and adapted to contact with said casing.

70 8. A battery hand lamp, comprising, a metal battery-receiving casing in the lamp circuit, an end cap mounted on said casing, an element mounted in but insulated from said cap and connected with the battery, and a flange on said casing adapted to contact with said element.

75 9. A battery hand lamp, comprising, a metal battery-receiving casing in the lamp circuit, an end cap mounted on said casing, an element mounted in but insulated from said cap, and a spring carried by said ele-

ment and engaging the battery, said element being adapted to contact with said casing.

10. A battery hand lamp, comprising, a metal battery-receiving casing in the lamp circuit, an end cap mounted on said casing, an element mounted in but insulated from said cap, a spring carried by said element

and engaging the battery, and a flange on said casing adapted to contact with said element.

10 In testimony whereof I affix my signature this 31st day of March, 1920.

ERNEST ALSCHULER.
